Primary Examiner — Janice Patyk(74) *Attorney, Agent, or Firm* — Honigman LLP; Kathryn D. Doyle; Jonathan P. O'Brien(57) **CLAIM**

We claim the ornamental design for a food container, as shown and described.

DESCRIPTION

FIG. 1 is a top perspective view of embodiment one, of a food container, shown in environmental use, showing our new design;

FIG. 2 is a top perspective view thereof;

FIG. 3 is a top plan view thereof;

FIG. 4 is a front elevation view thereof, a rear, side, and opposite side elevation views being identical;

FIG. 5 is a bottom plan view thereof;

FIG. 6 is a top perspective view embodiment two, of a food container, shown in environment use, showing our new design;

FIG. 7 is a top perspective view thereof;

FIG. 8 is a top plan view thereof;

FIG. 9 is a front elevation view thereof, a rear elevation view being a mirror image thereof; and,

FIG. 10 is a bottom plan view thereof.

The broken lines in the figures illustrate the portions of the design that form no part of the claimed design. The broken

(Continued)

lines container in FIGS. 1 and 6 illustrate environmental subject matter that form no part of the claimed design.

1 Claim, 6 Drawing Sheets
